Primary Examiner — Kevin K. Rudzinski*Assistant Examiner* — Evans David Delesline(74) *Attorney, Agent, or Firm* — ScienBiziP, P.C.(57) **CLAIM**

The ornamental design for a watch band, as shown and described.

DESCRIPTION

FIG. 1 is a front perspective view of a watch band, showing my design.

FIG. 2 is a rear perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof; and,

FIG. 8 is a bottom plan view thereof.

The broken lines shown in the drawings represent portions of the watch band that form no part of the claimed design.
